UNITED STATES PATENT OFFICE.

CHARLES DE BENEDICTIS, OF JERSEY CITY, NEW JERSEY.

DESIGN FOR A RUG.

Application filed November 28, 1927. Serial No. 24,315. Term of patent 3½ years.

To all whom it may concern:

Be it known that I, CHARLES DE BENEDICTIS, a citizen of the United States of America, and a resident of Jersey City, Hudson County, and State of New Jersey, have invented a new, original, and ornamental Design for a Rug, of which the following is a specification, reference being had to the accompanying drawing, forming part thereof.

The design resides in the particular combination of the outline of the rug, the parallel border, the arrangement of the motif in the center and the arrangement of the representations of the branches, leaves and birds in the motif.

I claim:

The ornamental design for a rug, as shown and described.

CHARLES DE BENEDICTIS.
